UNITED STATES PATENT OFFICE

157,371

BOTTLE HOLDER

Dorothy L. Halcomb, San Diego, Calif.

Application October 8, 1948, Serial No. 149,044

Term of patent 7 years

(Cl. D58—9)

To all whom it may concern:

Be it known that I, Dorothy L. Halcomb, a citizen of the United States of America, residing at San Diego, in the county of San Diego and State of California, have invented a new, original, and ornamental Design for a Bottle Holder, of which the following is a specification, reference being had to the accompanying drawing, forming part thereof.

Figs. 1, 2 and 3 of the drawing are a front, rear and side view, respectively, of a bottle holder, showing my new design.

Fig. 4 is a perspective view of the bottle holder of Figs. 1, 2 and 3 with the upper removable part separated from and laid alongside the base.

I claim:

The ornamental design for a bottle holder, as shown.

DOROTHY L. HALCOMB.
